UNITED STATES PATENT OFFICE.

HENRY WHITE, OF MILNOR, NORTH DAKOTA.

DESIGN FOR A CLOTHESPIN.

59,445.

Specification for Design.

Patented Oct. 18, 1921.

Application filed May 23, 1921. Serial No. 471,992. Term of patent 14 years.

To all whom it may concern:

Be it known that I, HENRY WHITE, a citizen of the United States, residing at Milnor, in the county of Sargent and State of North Dakota, have invented a new, original, and ornamental Design for Clothespins, of which the following is a specification, reference being had to the accompanying drawing, forming a part thereof.

Figure 1 is a perspective view of a clothespin, showing my new design.

Fig. 2 is an end elevation, and

Fig. 3 is a side elevation thereof.

I claim:

The ornamental design for a clothespin, as shown.

HENRY WHITE
